ATTORNEYS.

UNITED STATES PATENT OFFICE.

EVERETT R. SLAGLE, OF SAYRE, PENNSYLVANIA, ASSIGNOR TO STANDARD VACUUM BRAKE CO., OF CAMDEN, NEW JERSEY, A CORPORATION OF NEW JERSEY.

CARBURETOR.

Application filed April 13, 1926. Serial No. 101,693.

This invention, generally stated, relates to carburetors and has more especial relation to that type usually termed multiple valve carburetor.

5 The leading object of the present invention may be said to reside in the provision of a simple, efficient and compact carburetor of the multiple type the air inlets and liquid inlets of which are normally closed by valves 10 opening in opposite directions, of which valves the air controlling valve is arranged to be unseated a trifle in advance of the liquid controlling valve.

A further object of the present invention 15 is to provide a carburetor of the type recited in which a rocker arm is provided for carrying the air controlling valve at one end, the free end of said rocker arm being spaced from the liquid control valve by means of a 20 spring, whereby the air controlling valve must be unseated slightly before the liquid controlling valve can be unseated by the rocker arm.

A further object of the present invention 25 is to provide a carburetor of the character stated in which the casing is two-part and separated by a division plate which division plate is provided with an air port and a liquid port controlled by valves opening in 30 opposite directions.

A further object of the present invention is to provide an arrangement and construction of parts for attaining the function set forth in the aforesaid objects.

35 Other and further objects not at this time appearing will be hereinafter set forth.

The invention consists of the novel construction hereinafter described and finally claimed.

40 The nature, characteristic features and scope of the invention will be more fully understood from the following description taken in connection with the accompanying drawings forming part hereof, and in which:

45 Fig. 1, is a view in cross-section of a multiple valve carburetor embodying the invention.

Fig. 2, is a view in plan with the casing 2, as shown in Fig. 1, removed.

50 Fig. 3, is a fragmentary view illustrating details of construction of the liquid controlling valve shown at the right hand side of Fig. 1.

For the purpose of illustrating my invention I have shown in the accompanying

drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described. 60

1 designates my novel construction of carburetor, the same comprising a casing, which may be in two sections, an upper section 2 and a lower section 3 having the intermediate plate or partition 4 and the upper and lower gaskets 5 and 6, whereby an air-tight structure is produced, said casing sections and gaskets being held in assembled position by any suitable means. 65

7 designates a threaded nipple which is adapted to be screwed into the intake manifold of an internal combustion engine, said nipple communicating with the mixing chamber 8 within the casing section 2. 9 designates the air inlet for the admission of air under atmospheric pressure or less to the chamber 10, the exit therefrom being controlled by the air valve 11, which is mounted on the valve stem 12, which also carries the washer or the like 13. The upper end of the 75 valve stem is pivotally connected at 14 to the rocker arm 15, which is fulcrumed at the points 16. In order that the rocker arm 15 may be supported so that friction may be reduced to a minimum, I provide the pivot 80 screws 17 which are mounted in the lugs 18 and provided with the lock nuts 19, the inner ends 16 of said pivot screws engaging conical seats 20 on the opposite sides of the 85 rocker arm 15.

21 designates a spring bearing on the under side of the rocker arm 15 and tending to keep the valve 11 normally closed. 90

22 designates a valve stem, positioned in a port 23, in the partition 4, of somewhat 100 larger diameter than the valve stem 22, said valve stem carrying the gasoline controlling valve 24 at its lower end and at its upper portion being provided with a plurality of

105 adjusting nuts 25 for adjusting the tension of the spring 26 positioned between the lower of said nuts and the top of the partition 4. By making the port 23 larger than the stem 22 a sufficiently large passage is provided for the gasoline to flow freely to the desired 110

point. 27 designates a liquid inlet, for instance, for the admission of gasoline above which is the constantly open port 28 communicating with the chamber 29 below said valve 24. The nipple 7 is screwed into the intake manifold. In this position, when the motor is idling, there is created in its intake manifold and the passage 7 and chamber 8, a vacuum equivalent to 18 to 22 inches of mercury. Under these conditions, valve 11 is drawn from its seat permitting the admission of air at atmospheric pressure or less through the opening 9 into the chamber 10, and the movement of the valve 11, when the motor is started, will cause the rocker arm 15 to come in contact with the valve stem 22, causing the valve 24 to be moved from its seat thereby permitting the gasoline from a source of supply, which communicates with the passage 27, to be drawn through the ports 28 and 23 and thence into the mixing chamber 8, where it is mixed with the air being drawn from the chamber 10 and so passes through the passage or opening 7 into the intake manifold, causing the mixture in the intake manifold to be combustible thereby preventing the motor from stalling, which would be the case if any quantity of pure air unmixed with gasoline were admitted into the intake manifold. As the vacuum is increased, the movement of the valve 11 is correspondingly shortened and when the vacuum has increased to such a degree which is determined by the spring tension 26 on the valve stem 22, the valve 24 will close so that no additional gasoline will be mixed with the small quantity of air entering the motor under these conditions.

When the motor is stopped, the valve 11 prevents drawing air back through the motor which would tend to destroy the vacuum, so that this valve 11 is a combined check and mixing valve. The opening 27 communicates with a source of supply, which is preferably a tank of an automobile and inasmuch as when this valve 24 is in operation there is a vacuum in the chamber 8, it is of no importance whether or not the tank is below the mixing valve or above it, as the vacuum in chamber 8 would cause the gasoline line to flow through the ports 28 and 23.

By reason of the special, pivotal arrangement of rocker arm 15 which is normally under spring tension as at 21, atmospheric pressure or pressure less than atmospheric pressure causes the unseating of valve 11 a trifle in advance of the unseating of valve 24.

What I claim is:

1. In a carburetor, a casing comprising a

single upper and a single lower section having a partition, interposed between said sections, said lower section having an air inlet and a gasoline inlet, which inlets are oppositely disposed, an outlet in said upper section and arranged at right angles to said inlets and adapted to communicate with an intake manifold, a mixing chamber in the upper of said casing sections, valves seating for movement in opposite directions with respect to said partition and controlling the inlets to said mixing chamber, a rocker arm arranged in the chamber of said upper section and carrying at one end the air controlling valve which is arranged to open upwardly with respect to said partition, and having at its opposite end a gasoline valve arranged to move downwardly with respect to said partition, a spring for normally holding the latter valve upwardly to its seat, and a spring bearing on said rocker arm for normally holding the air valve down upon its seat, the free end of said rocker arm being adapted to unseat and depress said gasoline valve during the upward opening of said air valve.

2. In a carburetor, a casing comprising a single upper and a single lower section having a partition and upper and lower gaskets interposed between said sections, said lower section having an air inlet and a gasoline inlet which inlets are oppositely disposed, an outlet in said upper section and arranged at right angles to said inlets and adapted to communicate with an intake manifold, a mixing chamber in the upper of said casing sections, valves seating for movement in opposite directions with respect to said partition and controlling the inlets to said mixing chamber, a rocker arm arranged in the chamber of said upper section and carrying at one end the air controlling valve which is arranged to open upwardly with respect to said partition, and having at its opposite end a gasoline valve arranged to move downwardly with respect to said partition, a spring for normally holding the latter valve upwardly to its seat, a spring bearing on said rocker arm for normally holding the air valve down upon its seat, the free end of said rocker arm being adapted to unseat and depress said gasoline valve during the upward opening of said air valve, said rocker arm having oppositely disposed conical seats, and oppositely located adjustable pivot screws engaging said conical seats, said two-part casing containing all of said parts.

EVERETT R. SLAGLE.
